His Attorney.

UNITED STATES PATENT OFFICE

2,324,858

OUTLET GRILLE FOR AIR CONDITIONING APPARATUS

Samuel J. Levine, Verona, N. J., assignor to General Electric Company, a corporation of New York

Application January 2, 1941, Serial No. 372,745

6 Claims. (CL. 88—40)

My invention relates to outlet grilles for air conditioning apparatus and the like and particularly to adjustable outlet grilles for selectively determining the direction of air discharged into a room from the outlet of an air conditioning apparatus.

It is often desirable to change the direction of air discharged into a room from air heating or cooling apparatus in order to obtain the greatest advantage of the discharged stream in circulating air about the room, with maximum comfort to the occupants in the room. For example, it may be desirable to change the direction of the discharge stream depending upon the temperature of the discharged air. When employing air conditioning units which may be placed in different positions in the room, it may, for example, be desirable to discharge air at one angle when the conditioner is arranged to blow the air lengthwise of the room, and in another direction when it is arranged to blow the air in a direction crosswise to the room. It is desirable that the change of direction of air discharge be effected without the necessity of altering or taking apart portions of the apparatus.

It is an object of my invention to provide an outlet grille for air conditioning apparatus and the like including an improved arrangement for determining selectively the direction in which air is to be discharged from the outlet.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is an end elevation view particularly in section of a portion of an air conditioning unit having an outlet grille embodying my invention; Fig. 2 is a front elevation view of the unit shown in Fig. 1; Fig. 3 is an enlarged sectional view of the unit shown in Figs. 1 and 2 on the line 3—3 of Fig. 2; Fig. 4 is a perspective view of the operating member of the grille shown in Fig. 1; Fig. 5 is a view similar to Fig. 3 showing a modified form of my invention; and Fig. 6 is a perspective view of the operating member of the grille shown in Fig. 5.

The outlet grille shown in the drawing comprises generally a frame, casing or other suitable member in which is formed an elongated outlet opening adjacent one edge thereof and in which are arranged a plurality of elongated vanes

5 or louver members arranged to constitute, in effect, two sets, one set tending to direct the air discharged from the opening in one direction and the other set tending to direct the air in another direction. The air is discharged through only one set of vanes at a time and an elongated bar or other operating member is provided for shielding the set not in use. The bar is pivotally mounted so that it may be swung in either of two positions to select the desired direction of discharge of the air.

Referring now to the drawing, in Figs. 1 and 2 I have shown an air conditioning unit 10 adapted to be mounted on the floor of a room and having a fresh air inlet duct 11 for connection with a window opening and a conditioned air outlet comprising two openings 12 as indicated in Fig. 2 for discharging air into the room. The outlet is formed in a suitable frame 13 constituting a portion of the outer casing of the unit 10. Within the casing of the unit 10 there may be arranged the usual elements of an air conditioning apparatus, including a motor and a blower (not shown), a filter 14, and a heat exchanger 15. Furthermore, it is common practice to provide an inlet for admitting to the casing air from the room which may be mixed with the fresh air and circulated through the casing and over the heat exchanger. The heat exchanger 15, as illustrated, comprises a suitable coil provided with heat transfer fins 15a and through which may be circulated a heating or a cooling medium. After the air has passed over the heat exchanger 15, it is discharged through the outlet and into the room. Within the openings 12 are provided a plurality of louver members or vanes 16 which tend to force the discharged air to pass out of the openings at predetermined angles. The vanes 16, as illustrated, are thin, flat strips or slats, the edges of adjacent vanes being parallel but the flat sides being arranged at angles suitable to direct the air passing through the front and back of openings 12 at different angles. The vanes associated with each opening may be arranged in two sets, the vanes in each set having their flat sides parallel and all the vanes of one set being at the same angle with respect to the vanes of the other set. However, I prefer to arrange the vanes so that their flat sides lie in radial planes passing through a common axis. When the vanes are arranged in this manner, the successive vanes from right to left, as viewed in Figs. 1 and 3, direct the air more away from the vertical. By arranging the vanes to direct the air successively more away from the vertical,

their spacing as viewed from the outside of the unit is uniform. In order to determine selectively the direction at which the air is to be discharged, I provide a shielding member 17 below and adjacent the louvers 16 and pivotally mounted within the frame 13 on pins 18 at either end thereof. The member 17 has been shown as an elongated bar or channel member mounted on arms 19 at either end thereof which are pivoted on pins 18. The bar 17 may be in either of two positions. In Fig. 1 it has been shown in a position to shield the two left hand vanes 16, and in Fig. 3 it has been shown shielding the two right hand vanes. The central or middle vane 16 cooperates with either of the two sets or pairs of outside vanes; this makes it unnecessary to shield an entire half of the opening, and the bar 17, in fact, covers only about one-third of the opening. The middle vane is, therefore, in a somewhat neutral location. When the bar 17 is in the left hand position, as shown in Fig. 1, the direction of the air discharged through the openings 12 is more to the vertical than when the bar is in a position as shown in Fig. 3, and the right and left hand groups of vanes thus constitute two sets of vanes, each set tending to direct the air in a different direction. In order to adjust the position of the bar 17, I provide a handle 20 extending through a suitable transverse opening 21 formed in a portion 22 of the frame 13 between the two openings 12. The bar 17 is thus arranged to shield those vanes which are not to be used.

During the operation of the air conditioning unit shown in Fig. 1, when it is desired to direct the air in a substantially upright direction, the handle 20 is positioned to place the bar 17 forwardly as indicated in Fig. 1; and when it is desired to direct the discharged air forward from the unit, the handle 21 is moved to place the bar 17 in its position toward the rear as shown in Fig. 3 so that the air is directed forwardly by striking the left hand vanes 16.

In Fig. 5 I have illustrated another embodiment of my invention which makes it possible to select any of a plurality of groups of the vanes 16 so that the direction of the air may be varied progressively from one side of the outlet to the other. Fig. 5 is similar to Fig. 3 and corresponding parts have been designated by the same numerals. In this construction I have provided a segmental sheet metal member 23 having an elongated opening 24 in the central portion thereof through which the air is discharged toward the vanes 16, the opening 24 being of less width than the openings 12. The member 23 is pivoted at 25 on arms 26 so that it may be arranged with the opening 24 in any desired position below the vanes 16 to select a particular group of the vanes 16. A suitable handle (now shown) similar to the handle 20 extending through the slot 21 of Fig. 3 may be provided to move the member 23 to its desired position. The construction of the member 23 is more clearly shown in Fig. 6 where it will be seen that the corners have been cut away as indicated at 27 so that the member 23 may be moved past the end plates of the heat exchanger 15, the fins being sufficiently far back of the end plates that they do not interfere with the movement of the member 23. During the operation of the grille illustrated in Fig. 5, the direction of the air to be discharged from the openings 12 may be selected by placing the damper member 23 in any desired position, the direction of the air changing progressively toward the vertical as the damper is

moved from its left hand position as shown in Fig. 5 toward a right hand position in which the arm 26 is substantially vertical.

From the foregoing it will be apparent that I have provided a simple and effective arrangement for selectively determining the direction of air to be discharged from the outlet grille of an air conditioning apparatus. With this arrangement it is unnecessary to provide adjustable vanes or louvers and the adjustment may be made instantly without the use of tools and without the necessity of bending or turning parts of the grille.

While I have shown my invention in connection with an air conditioning unit adapted to be mounted on the floor, other applications will readily be apparent to those skilled in the art. I do not therefore desire my invention to be limited to the particular constructions shown and described and I intend in the appended claims to cover all modifications within the spirit and scope of my invention.

What I claim as new and desire to secure by Letters Patent of the United States, is:

1. An outlet grille for air conditioning apparatus and the like comprising a member providing an outlet opening, a plurality of vanes associated with said opening, said vanes being arranged in two sets, one set for directing air flowing through the opening in one direction and the other set for directing the air in a different direction, and means including a member movable into either of two positions to shield one of said sets of vanes in one position and the other of said sets in its other position for selectively determining the direction of flow of air discharged through the opening.

2. An outlet grille for air conditioning apparatus and the like comprising a member providing an outlet opening, a plurality of vanes associated with said opening, said vanes being arranged in two sets, one set for directing air flowing through the opening in one direction and the other set for directing the air in a different direction, and means including a bar swingably mounted to be movable into either of two positions to shield one of said sets of vanes in one position and the other of said sets in its other position for selectively determining the direction of flow of air discharged through the opening.

3. An outlet grille for air conditioning apparatus and the like comprising a member providing an outlet opening, a plurality of elongated flat vanes associated with said opening, the flat sides of said vanes being arranged in substantially radial planes with respect to a common axis and being arranged so that the direction of the air passing through said opening is varied progressively from one side of the opening to the other, and means including a member movable into either of two positions to shield a portion of the vanes at one side of the opening in one position and a portion of said vanes at the other side of said opening in its other position for selectively determining the direction of flow of air discharged through the opening.

4. An outlet grille for air conditioning apparatus and the like, comprising a member providing an outlet opening, a plurality of elongated flat vanes associated with said opening and having their longitudinal edges parallel, said vanes being arranged in two sets, the flat sides of one set being arranged for directing air flowing through the opening in one direction and the flat sides of the other set being arranged for directing the air in a different direction, and means including

a bar swingably mounted to be movable into either of two positions to shield one of said sets of vanes in one position and the other of said sets in its other position for selectively determining the direction of flow of air discharged through the opening.

5. A cabinet for air conditioning apparatus and the like, comprising a substantially rectangular casing having an elongated opening extending parallel to and adjacent one edge thereof, a plurality of elongated flat vanes mounted in said opening and having their longitudinal edges parallel mounted, said vanes being arranged to constitute two sets, the flat sides of the vanes of one set being arranged to direct the air at one predetermined angle from said opening and the flat sides of the vanes of the other set being arranged to direct the air at another predetermined angle from said opening, and means including an elongated member pivotally mounted within said casing to be movable into either of two positions to

shield one of said sets of vanes in its first position and the other of said sets of vanes in its second position for selectively determining the angle at which air is to be discharged from said opening.

6. An outlet grille for air conditioning apparatus and the like comprising a member providing an outlet opening, a plurality of elongated flat vanes associated with said opening, the flat sides of said vanes being arranged in substantially radial planes with respect to a common axis and being arranged so that the direction of the air passing through said opening differs progressively from one side of the opening to the other, and means including a movable damper member having an elongated opening therein of a width less than that of said outlet opening for selectively determining the direction of flow of air discharged from said outlet opening.

SAMUEL J. LEVINE.
